Primary Examiner — Rhea Shields(74) Attorney, Agent, or Firm — Price Heneveld LLP(57) CLAIM

The ornamental design for a dispensing brush, as shown and described.

DESCRIPTION

FIG. 1 is a front perspective view of a dispensing brush according to the design;

FIG. 2 is a bottom perspective view thereof;

FIG. 3 is a front elevation view thereof;

FIG. 4 is a back elevation view thereof;

FIG. 5 is a right side elevation view thereof;

FIG. 6 is a left side view thereof;

FIG. 7 is a top plan view thereof; and,

FIG. 8 is a bottom plan view thereof.

The portions of the article shown in broken line form no part of the claimed design.

1 Claim, 8 Drawing Sheets(56)
